(57) **CLAIM**

The ornamental design of an air fryer as shown and described.

DESCRIPTION

FIG. 1 is a top, front, side perspective view of an air fryer showing my new design;

FIG. 2 is a top, rear, side perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the figures are included for the purpose of illustrating portions of the air fryer and do not form any part of the claimed design.
